UNITED STATES PATENT OFFICE.

CARL GESKE, OF GRAND RAPIDS, MICHIGAN, ASSIGNOR TO WINTERS & CRAMPTON MANUFACTURING COMPANY, OF GRAND RAPIDS, MICHIGAN, A CORPORATION OF MICHIGAN.

HINGE.

Application filed September 19, 1927. Serial No. 220,327.

This invention relates to a hinge, being more particularly concerned with a novel construction of hinge member and method of making the same. It is common to make 5 hinges wherein one hinge member comprises a base plate with spaced apart lugs projecting therefrom between which one end of the other hinge member is located, a pivot pin extending through said lugs and the end of the other 10 hinged member disposed between them. The lugs project at right angles from the plane of the base plate and heretofore it has been the most common practice to make the first hinge member as a casting the lugs being cast integral with the base plate.

The cast base plate and lugs are open to many objections, the principal one of which is that it is impossible to accurately cast to a degree such that the hinge member which 20 is to be disposed between the lugs shall fit the same properly necessitating that the lugs be machined in order to secure the proper entrance of the other hinge member between them. In addition cast metal, particularly 25 brass which is the metal most commonly used in making hinges of this type for refrigerators is soft and porous and is liable to be deficient in strength so that the hinge in many instances does not stand up in service.

In the present invention a novel method 30 has been devised for producing the base plate with projecting lugs all parts thereof being stamped and readily formed on a punch press and after formation readily assembled, using 35 a punch press. The base plate is of rolled brass or similar metal and is toughened and strengthened by reason of the rolling process to which it has been subjected. The lugs are made from rolled bars of metal and during 40 their formation from such bars are further machined and worked so as to be toughened and tempered and greatly increased in strength.

An understanding of the invention may be 45 had from the following description taken in connection with the accompanying drawing, in which,

Fig. 1 is a perspective view of a complete hinge made in accordance with my invention. 50 Fig. 2 is a perspective view of one of the hinge members showing the base plate and

the lugs which are to be permanently secured thereto.

Fig. 3 is a perspective view of the hinge member after the lugs have been permanently 55 secured to the base plate.

Fig. 4 is a fragmentary enlarged section illustrating the assembly of a lug with the base plate previous to the punch press operation which permanently secures the two together.

Fig. 5 is a similar view illustrating said lug and base plate after the operation of securing them together has been performed.

Fig. 6 is a fragmentary perspective view, 65 similar to that shown in Fig. 3, wherein a slight modification in the form of the lug and base plate is illustrated, and

Fig. 7 is a view similar to Fig. 5 with reference to the slightly modified form.

Like reference characters refer to like parts in the different figures of the drawing.

The first operation in forming one of the hinge members is to provide a base plate 1 of flat metal of any suitable outline through 75 which spaced apart openings are made and, preferably, the metal around the opening pressed outwardly making a raised embossing 2 around each opening. This is performed on a punch press and at the under side of the plate below the embossing the opening which the embossing surrounds enlarges downwardly and outwardly as indicated at 3.

The lugs 4 one of which is to be attached 85 to the base plate at each of said openings 2 are cut from flat bar stock and then shaped in a punch press so as to somewhat compress and thicken the upper ends of the lugs with the formation of an annular shoulder 5 between the lower edges of the lugs 4 and a depending integral section 6 which extends from the lower end of each lug 4 and is of a size to freely pass through and fit in an opening surrounded by an embossing 2.

The formation of the shoulder 5 is such 95 that when a lug is applied to the base plate by inserting the lower end portion 6 through one of the openings, the shoulder bears directly against the upper edges of the embossings 2 and the part 6 extends through the opening 2 a considerable distance. Then by

means of a suitable die and punch the part 6 is upset and thickened and reduced in height and spread out so as to completely fill the flared and widened portion 3 of the opening 5 2, as shown in Fig. 5 at 6^a, thus making a very permanent and secure connection of the lug to the base plate. Both lugs 4 may be attached to the base plate at one and the same time and when attached the lines of demarcation 10 between the lugs 4 at the shoulders 5 and the upper edges of the embossings 2 are practically invisible and disappear entirely upon finishing the hinge member with the usual buffing and polishing operations, particularly if plated as most hinges are when 15 used for refrigerators.

It is not necessary to raise the embossing 2 around an opening through the base plate but a rectangular opening may be made 20 through the base plate countersink and enlarged on the under side of the plate. The lug 4 in such instances will not have as long a projection portion 6 as as much metal is not needed to fill the countersink, but when the 25 lug is attached the countersink is filled completely, as indicated at 6^b in Fig. 7, the shoulder 5 bearing directly against the upper side of the base plate 1.

The lugs 4 adjacent the upper ends have 30 aligned openings therethrough. The other hinge member comprises a plate 7 one end thereof being formed into a roll 8 which, passing between the two spaced apart lugs 4, is connected to said lugs by a hinge pin 9 35 passing through the openings in the lugs and lengthwise of the roll 8 headed at its ends to make a permanent and secure hinge connection.

When constructed in the manner described 40 it is not necessary to machine the lugs 4 at all inasmuch as with proper dies the parts may be fabricated to very close limits. The lugs 4 particularly are very strong and durable being in the first instance made of rolled 45 metal which in the forming of the lug is considerably worked and toughened and tem-

pered with a corresponding increase in strength. This method of forming a hinge member of the type illustrated is very practical and efficient and there may be produced 50 with dies an exceptionally practical and serviceable hinge member structure equal in every respect to drop forging in quality with a complete elimination of the difficulties and extra expense of drop forging operations. 55

I claim:

1. The herein described method of producing a hinge member which consists in providing a base plate of flat metal having two spaced apart openings therethrough, said base plate around each opening being pressed upwardly to form an upwardly and inwardly tapered embossing around said opening through the base plate, said openings at their lower ends being larger than at their upper ends, inserting a lug through each opening each of said lugs having a horizontal shoulder around it between its ends with a section below said shoulder adapted to freely pass through the opening in the base plate, and then upsetting, riveting and thickening said reduced section to fill the lower enlarged end portions of said openings through the base plate and draw the shoulder on each lug tightly into engagement with the upper edge 75 of each embossing around each opening.

2. The herein described method of producing a hinge member which consists in providing a base plate of flat metal having an opening therethrough, said base plate around the opening being raised to form a boss, inserting a lug through the opening, said lug having a shoulder between its ends with a section below the shoulder adapted to freely pass through the opening in the base plate 80 and then riveting said reduced section at the under side of the base plate to draw the shoulder on the lug tightly into engagement with the upper side of said boss. 85

In testimony whereof I affix my signature.

CARL GESKE
